UNITED STATES PATENT OFFICE.

JAMES B. GARNER, OF PITTSBURGH, PENNSYLVANIA, AND HOWELL C. COOPER, OF CLARKSBURG, WEST VIRGINIA, ASSIGNEES TO HOPE NATURAL GAS COMPANY, OF PITTSBURGH, PENNSYLVANIA, A CORPORATION OF WEST VIRGINIA.

RECOVERY OF BUTANE AND PROPANE.

1,307,353.

Specification of Letters Patent. Patented June 24, 1919.

Application filed August 5, 1916. Serial No. 113,300.

To all whom it may concern:

Be it known that we, JAMES B. GARNER, residing at Pittsburgh, county of Allegheny, and State of Pennsylvania, and HOWELL C. COOPER, residing at Clarksburg, in the county of Harrison and State of West Virginia, both citizens of the United States, have invented or discovered certain new and useful Improvements in the Recovery 10 of Butane and Propane, of which improvements the following is a specification.

Our invention relates to the recovery from hydrocarbons, such as petroleum and natural gas and derivatives thereof, of liquid butane and propane separately in substantially pure condition. These hydrocarbons, butane and propane, are known to be constituents, in varying proportions, of natural gas and of oil also. They are 20 gases under normal atmospheric conditions of pressure and temperature. Aside from their existence in such hydrocarbon mixtures of natural origin, there is, to the best of our knowledge, no other known source of butane and propane, and such as have been commercially produced have been prepared synthetically. But although known to be constituents of hydrocarbon mixtures of natural origin, their separation from such 30 mixtures has not heretofore been accomplished commercially. However, if obtained economically on a commercial scale, each substance has great commercial value as a liquefied homogeneous combustible gas suitable, 35 for example, for heating, for cutting and welding metals, and for internal combustion engines.

For various reasons it is essential that a liquefied hydrocarbon gas for such purposes 40 be homogeneous. In the first place, for shipment it must, of course, be placed in pressure flasks, and it is necessary, in fact it is a requisite for interstate shipment, to know the pressure to which such filled flasks 45 may, under different temperatures, be subjected. If the liquid be not a homogeneous substance, the pressure which it will exert on its flask or container cannot, because of varying partial pressures, be predicted. In 50 the second place, if the liquid gas be not a homogeneous substance, that is to say, if it be a mixture of various hydrocarbons, the first gas used from a filled flask will include in its mixture a larger percentage of the

lighter and more volatile hydrocarbons than will the gas last used. Consequently, the heating value or B. T. U. of the gas from a single flask will vary as the flask is emptied, the gas first used having a lower B. T. U. than that last used; the amount of oxygen required to be mixed with the gas will vary; and a burner, jet or carbureter suitable for the first portion of the gas delivered from the container will be unsuitable for the last portion delivered therefrom.

In the course of our experimentation we have endeavored in vain to separate these components from natural gas containing them, by subjecting the gas directly to the normal operation of fractional condensation: that is to say, by gradually increasing pressure, to condense one component after another, as the point of liquefaction of the several components is successively attained. For reasons not certainly known butane and propane cannot be thus separately recovered.

In an application for United States Letters Patent filed by us on June 8th, 1916, Serial No. 102,489, we have described a process of obtaining gasoline from natural gas consisting in certain improvements upon the process for that purpose described and claimed in United States Letters Patent No. 989,927 to George M. Saybolt, one of the purposes of the said improvements being the more effective separation from the normal liquid product of the said Saybolt process, of the so-called lighter combustible constituents of the gas. In the practice of the present invention we prefer to employ the apparatus shown in the drawings of our said pending application, and it is therefore illustrated in Figures 1 and 2 of the accompanying drawings. Fig. 3 shows a form of apparatus which we prefer to employ for the performance of the last steps of our present invention. It will be understood however that other forms of apparatus may be used if desired, and that shown may also be considerably varied.

Referring first to Fig. 1, the natural gas from a well or series of wells 1 is shown as passed through a compressor 2, by which it is compressed, and thence passes through a cooler 3, and by pipe 6 into the lower absorber 4 of a pair of absorbers 4 and 5. The portion of pipe 6 within the absorber 4 is

perforated, as indicated, so that the compressed gas is made to bubble up through a body of absorbent menstruum as will presently be described. The gas which is unab-
5 sorbed by the menstruum in the absorber 4 is caught in a perforate pipe or header 7, and thence passes through a pipe 8 to a perforate pipe 9 near the bottom of the absorber 5, and thence flows through absorbent men-
10 struum contained in this absorber. The re-
mainning unabsorbed gas is caught in a per-
forate pipe or header 10 and flows out
through the pipe 11 to the gas line.

The absorbent menstruum is made to flow
15 through the absorbers in a direction opposite
to that of the flow of the gas. The men-
struum enters the absorber 5 through the
pipe 12, and, as viewed in Fig. 1, flows from
right to left to a pipe 13 leading downwardly
20 into the left end of the absorber 4,
through which it flows from left to right to
a pipe 14. Suitable partitions or dams 15,
16 are provided in the absorbers in order to
maintain therein a body of menstruum of
25 suitable depth.

As is stated in the Saybolt patent above
referred to various liquids may be used as an
absorbent menstruum. We prefer to use
however a petroleum hydrocarbon having an
30 initial Baumé gravity of from 28° to 55°, at
60° Fahrenheit. When the apparatus is op-
erated as thus far explained, under condi-
tions of pressure and temperature well un-
derstood by those skilled in the art, the re-
35 sult is the absorption in the menstruum con-
tained in the absorbers 4 and 5 of vapors
which are contained in the natural gas and
which when condensed constitute what is
commercially known as gasoline, together
40 with certain other lighter hydrocarbons, in
varying quantities dependent upon condi-
tions of operation, which are gaseous at at-
mospheric pressure and temperature, and
which include butane and propane.

45 From the absorber 4 the menstruum, now
enriched by the hydrocarbons which it has
been caused to absorb from the natural gas,
flows through the pipe 14 into the primary
50 still, consisting of the upper retort 17 and
the lower retort 18, which may be heated to
the desired degree in any suitable way, but
preferably by means of the steam pipes to be
presently described. In the apparatus illus-
55 trated, the pressure of the absorbers is main-
tained in the still, and in order to prevent
gas from flowing from the absorber 4 into
the retort 17, or the vapor from the retort 17
flowing into the absorber 4, a trap 19 is
60 formed in the pipe 14, the vertical length of
each leg of which is such as to provide a
column of the liquid enriched menstruum of
sufficient weight to overcome all permissible
or likely difference in pressure between the
65 absorber 4 and the retort 17.

65 In the top of the retort 17 is a perforate

pipe or header 20, through which the en-
riched menstruum is conducted from the pipe
14 and from which it flows over the steam
pipes within the retort. From the bottom of
70 the retort 17 the menstruum flows through a
pipe 21 into the bottom of the retort 18,
through which retort it flows, in a devious
path determined by the baffle plates 22, to
the discharge pipe 23. In the apparatus
75 shown a supply of hot water or steam is
taken from the heater 24 (Fig. 2) and flows
through a pipe 25 into the retort 18, and
from thence through a pipe 26 into the pipes
in retort 17, and thence out through an es-
cape pipe 27.

80 The function of the retorts 17 and 18 is to
distil off from the enriched menstruum pre-
ferably only lighter constituents which have
been absorbed from the gas, and which are
gaseous at atmospheric pressure and tem-
85 perature. Hence the temperature main-
tained in these retorts is comparatively low,
say from 95° to 110° F. And the pressure, as
already stated, approximates the pressure in
the absorbers, so that those hydrocarbons
90 which have been absorbed from the gas
which are liquid at atmospheric temperature
and pressure shall remain for the most part
still contained in the enriched menstruum.

95 The lighter hydrocarbons which are dis-
tilled out of the enriched menstruum in the
retorts 17 and 18 pass from the retort 18
through the pipe 28 into the retort 17, and
thence all of such distilled hydrocarbons
100 pass out of the retort 17 through the pipe
30; or in the alternative the hydrocarbon
vapors in the retort 18 may pass out through
the pipe 29 into pipe 30. From the pipe 30
these lighter gaseous hydrocarbons may pass
105 directly through the pipe 31 into the line 11;
or, as described in our application referred
to; they may be pumped by the pump 32 in
the pipe 33 through a cooler 34 and liquefied
products be deposited in receptacle 35, while
110 still uncondensed vapors may pass through
the pipe 36 to the line 11. Or the apparatus
may be operated under such conditions of
pressure and temperature, as is well under-
stood in the art, that the vapors in the pipe
115 30 may be passed to the devices hereinafter
described for the recovery of propane and
butane.

120 After the primary distillation of the en-
riched menstruum in the retorts 17, 18, under
considerable pressure and comparatively low
temperature, the enriched menstruum is
preferably subjected to a second distillation,
in order to obtain from it those hydrocarbons
which have been absorbed from the natural
gas which constitutes the liquid gasoline of
125 commerce, these being mainly pentane, hex-
ane, heptane, and octane. This gasoline dis-
tilling operation is effected under a lower
pressure and at a higher temperature than
the primary distillation. Referring now to
130

Fig. 2, the menstruum (still containing the "gasolene" hydrocarbons and usually still some of the lighter hydrocarbons) passes from the bottom of the retort 18 through 5 the pipe 23, which is provided with a pressure reducing valve 45, into the heat exchanger 43, whence it passes through the pipe 46 into the still 38. Within the heat exchanger 43 there is arranged a pipe system 10 into which flows from the still 38 through the pipe 44 the hot denuded menstruum, which serves to heat the enriched menstruum flowing through the exchanger 43 on its way to the still 38. The lower part 15 of the still 38 is provided with suitable pipes adapted to be heated by steam flowing from the header 39 at one end of the still to a similar header 40 at the other end thereof, these headers being provided with suitable 20 steam connections. However steam may be admitted directly to the still 38 through the jets 41 connected to a steam supply pipe 42. Within the still 38 there are arranged suitable baffles 54 to cause the menstruum to flow 25 in a devious path from one end to the other.

Because of the reduced pressure and the increase of temperature of the enriched menstruum in the heat exchanger 43, some of the contained hydrocarbons may be volatilized, and in order not to interfere with the distillation in the still 38 it is desirable that 30 these vapors be drawn off through a trap 47 connected to the pipe 46. They will pass out from the trap 47 through the pipe 48, which, as in the case of the pipe 30, may be connected either to the gas line, to a condenser, or to the butane and propane recovery devices, dependent upon the intended operation of the apparatus, which as has already 35 been stated may be regulated according to well known rules.

The conditions of temperature and pressure within the still 38 are such as to effect the distillation from the enriched menstruum 40 of its absorbed gasolene content, usually however together with certain quantities of gaseous propane and butane. The distilled vapors pass out from the still 38 through the pipe 49 (which may be provided with a 45 suitable steam ejector 51) into the condensing coils 50, from which the liquid product flows through the pipe 53 into the closed storage tanks 52, 52^a. The water, if any, and the gasoline, will be separated in the 50 storage tanks, and each may be drawn off separately as desired or found necessary. The pressure in the still 38, condenser coils 50, and tanks 52 and 52^a may be maintained 55 below a desired maximum by the use of a suitable relief valve placed in a tap 79 connected to the pipe 59 leading from the tops of the storage tanks.

The still uncondensed vapors (namely butane and propane) in the storage tanks 52, 60 52^a, pass out through the pipe 59. In order

to insure the attaining of a substantially pure mixture of gaseous butane and propane uncontaminated by any heavier hydrocarbon vapors, we preferably pass the uncondensed gases in the pipe 59 through a supplemental absorber or absorbers, wherein any pentane or other heavier hydrocarbon remaining in vapor form in the uncondensed gas will be absorbed, and a substantially pure mixture of butane and propane will be obtained for 70 further treatment. To this end we have shown the pipe 59 connected by pipes 60 and 61 with the bottoms of a pair of absorbers 55 and 56, which are adapted to contain a menstruum capable of absorbing any of 75 these heavier hydrocarbons. This menstruum will preferably be what is commercially known as "sun spirits", a liquid hydrocarbon of the paraffin series having at 80 60° F. a Baumé gravity of about 33.7°. The filtration will conveniently be carried on under normal atmospheric conditions of pressure and temperature. It may if preferred be carried on at a pressure greater than atmospheric, but less of course than the 85 liquefaction pressure of butane. The subdivision of the gas under treatment such as to cause it to bubble up through the menstruum in a finely divided state, and so to come into more intimate contact with the 90 menstruum and to be more thoroughly cleansed and purified, will be accomplished according to the well recognized principles of that operation. Connections are shown in the drawings whereby the gaseous substances in the pipe 59 may be caused to flow through the absorbers 55 and 56, either in series or in parallel, but such connections and the appliances connected therewith are well understood and need not be herein described in detail.

From the tops of the absorbers 55 and 56 the unabsorbed gases, now substantially a mixture of pure butane and pure propane flow, through the pipe 67 into the pipe 68 100 shown in Fig. 3 of the drawings, and thence into a container 69.

This container is a compression-chamber, and, in our operations on commercial scale in the field, has taken the form of a five-inch pipe 125 feet long laid up and down hill on a slope, so that there is a gravitation of heavier from lighter components toward one end. This compression chamber is initially closed, except for the inlet 68, 115 and through this inlet the mixture to be treated is introduced in increasing quantities and with increasing pressure.

We continue to pump into this compression-chamber quantities of the gas to be reduced until, in consequence of increasing pressure, a liquefaction has taken place. The occurrence of such liquefaction may be detected by opening from time to time one and another of the pet cocks 70 with which 125

the compression chamber 69 is equipped at intervals throughout its length. Our work in the premises has had to do with a mixture of butane and propane in substantially equal proportions, and with such a mixture we have found that, when using the apparatus shown herein the initial liquefaction takes place at a pressure of about 130 pounds to the square inch. And we have discovered that this initial liquefaction is a liquefaction of the butane component alone, the propane component remaining at this pressure a gas. The thus liquefied butane collects at the lower end of compression chamber 69, whence it is drawn off by gravity, through a valve-controlled duct 71, to a suitable storage tank 72. The inlet pipe 68 will meanwhile preferably have been closed. Thus a fractional condensation is achieved upon a natural-gas derivative which has been essayed in vain upon the gas itself.

When the butane in liquid condition has been so drawn off there remains in compression-chamber 69 a body of substantially pure propane in gaseous form. The further operation involves compression of the propane to the point of liquefaction; this may be accomplished in any desired manner, and we shall here describe the means we have actually used, though other means manifestly may be employed. Water impelled by pressure is introduced at the lower end of compression-chamber 69 through a suitable connecting pipe 73, and this entering column of water is forced in, mounting up in chamber 69 and compressing the propane at the upper end of the chamber, until (under unmodified temperature conditions) a pressure upon the gas of about 650 pounds to the square inch is attained. At this point the propane liquefies (a change which, again, may be detected at pet-cock 70, or otherwise). When the propane has been so liquefied a duct 74 is opened, and through it the liquid propane is driven by the mounting column of water, through a cooler 75, if need be, to a storage tank 76. As the column of water mounts in the chamber 69, driving liquid propane before it, the height of its rise may be detected at the pet-cocks, and when it is detected at pet-cock 70 at the upper end of the pressure-chamber, the impelling pressure is cut off and duct 74 is closed. The storage tanks 72 and 76 may then be detached; valves may then be opened, the pressure-chamber drained, fresh storage tanks supplied, and the apparatus will thus be made ready for repetition of the operation now described. 77 is a pressure-gage which we have found convenient to employ to assist and facilitate our work. Pressure gages may be used elsewhere, if desired.

Our work in the premises (as has been

intimated above) has had to do with a natural-gas derivative in which the butane and propane components are, in terms of weight, present in substantially equal quantities. It is conceivable (though the fact lies beyond the range of our experimentation) that, given a gas in which these components are present in distinctly unequal proportions, some variation may be found in pursuing our method in the critical pressure required to condense and separate the butane component from the propane. While we have in the ensuing claims defined our invention according to the specific pressures which, under existing conditions, we have found correct, we recognize as within the scope of our invention and mean to include within the meaning of our claims such departures from the figures given, in this matter of critical pressure, as, in the case of compounds of other proportions, experience may find requisite. Of course, if for any reason it is found desirable to operate at temperatures other than substantially normal atmospheric, the critical pressures will vary accordingly, and we mean to include in the scope of our Letters Patent pressures equivalent to the pressures given—proper allowance being made for substantial departures from normal atmospheric temperature.

We have described our invention as having to do with natural gas, and, more specifically, with certain refined derivatives of natural gas. It will be understood that mixtures of butane and propane may be derived also from petroleum, and we mean to include within our invention as defined by Letters Patent the treatment of such mixtures, from whatever particular source derived.

We claim as our invention:

1. The method herein described of recovering butane from petroleum and natural gas and derivatives thereof which consists in isolating a substantially pure mixture of butane and propane alone and then subjecting such mixture to fractional condensation.

2. The method herein described of recovering butane and propane separately and each in liquid form which consists in isolating a substantially pure mixture of butane and propane alone, forcing the mixture into a suitable chamber until the condensation pressure of butane is reached and the butane component of the mixture in liquid form gravitates to the bottom of the chamber, then drawing off the butane; next in compressing the propane remaining in said chamber to the point of condensation, and finally in forcing the liquefied propane from said chamber.

3. The process of recovering butane from a gaseous mixture of butane, propane and other hydrocarbons, which consists of isolat-

ing a substantially pure mixture of the butane and propane alone, and then separating said mixture of butane and propane into its constituent elements.

5 4. The process of recovering butane from a gaseous mixture of butane, propane and other hydrocarbons, which consists of subjecting such mixture to an absorbing menstruum and by the aid thereof absorbing the
10 butane and propane, distilling said menstruum for the removal therefrom of butane and propane, subjecting the distillate to a substance capable of absorbing from the distillate the hydrocarbons heavier than butane, and separating the remaining substantially pure mixture of butane and propane into its constituent elements.

15 5. The process of treating a gaseous mixture of butane, propane and hydrocarbons heavier than butane, which consists of subjecting such mixture to a liquid hydrocarbon of about 33.7 Baumé gravity and by the aid

of said liquid absorbing said heavier hydrocarbons, and then separating the remaining gaseous mixture of propane and butane into 25 its constituent elements.

6. The method herein described of treating natural gas which consists in absorbing in a suitable menstruum its naphtha components together with its butane and propane components; second, in separating by distillation the butane and propane components; third, in filtering the distillate through a naphtha-absorbing substance; and, finally, separating the butane from the 35 propane by fractional condensation.

In testimony whereof we have hereunto set our hands.
